DISPLAY STAND FOR CARPET SAMPLES AND THE LIKE

Leon H. Best, Galva, and Robert D. Davis, Kewanee,
Ill., assignors to John H. Best & Sons, Inc., Galva, Ill.

Filed Jan. 24, 1972, Ser. No. 220,563

Term of patent 14 years

Int. Cl. D20—02

U.S. Cl. D6—139

FIG.3

FIG. 1 is a front view of the display stand for carpet samples and the like with the display panel thereof facing the viewer;

FIG. 2 is a side view of the stand with the panel facing the viewer having been turned 90° from the FIG. 1 position; and

FIG. 3 is a perspective view of the stand.

We claim:

The ornamental design for a display stand for carpet samples and the like, substantially as shown.
